UNITED STATES PATENT OFFICE.

HERBERT H. HULL, OF CLEVELAND, OHIO.

FOUNT FOR VAPOR-STOVES.

SPECIFICATION forming part of Letters Patent No. 351,774, dated November 2, 1886.

Application filed April 29, 1886. Serial No. 200,558. (No model.)

To all whom it may concern:

Be it known that I, HERBERT H. HULL, of Cleveland, in the county of Cuyahoga and State of Ohio, have invented certain new and useful Improvements in Founts for Vapor-Stoves, of which the following is a specification.

This invention relates to tilting founts for vapor-burning stoves; and it consists in the peculiar construction and combination of parts comprising the filling-neck and a valve mechanism contained therein, as hereinafter described, and pointed out in the claim.

In the accompanying drawing the figure shown represents top portion of a vapor-stove having my improvement in founts attached, showing the fount in the upright position with valve closed, and the fount tilted with valve open.

20 A represents a tin fount of the customary size and proportions used on vapor-stoves, and provided with the ordinary feed-pipe, *a*.

B is a funnel-shaped filling-neck attached horizontally to the upper corner of the fount, and is provided with a downwardly-extending branch tube, C, to the side of which is attached a diagonal chamber, D, connecting the neck B with the lower portion of said branch tube C, said neck B having an opening, *b*, and the tube C having an opening, *c*, by which communication is made from the neck into the tube C.

E is a ball-valve, having its seat in the open end of the tube C, which closes the communication from the neck into the fount when the fount is in the upright position, but is free to roll away from the seat when the fount is tilted over.

The operation of this valve mechanism is as follows: While the fount is in the upright position it is impossible to fill it, for the reason that the ball closes the communication, making it necessary to tilt the can over to open the said communication, and in order to open said communication the can must be tilted down a little below the horizontal position to let the ball roll away from the seat. The object of thus tilting the fount away down is that the supply shall be entirely cut off from the burners and prevent the possibility of pouring fluid into the fount when partially tilted down and the burners still burning, which is likely to be the case where this valve is not used in vapor-stoves in which a cut-off is provided in the joint of the supply-pipe. In thus tilting the fount down below the horizontal line the pressure of the flow in the supply-pipe is taken off from the burners, thereby extinguishing the fires before the fount can be refilled, which results in rendering the filling of the fount absolutely safe, so far as the connection of the burners is concerned.

Having described my invention, I claim—

The combination of a tilting vessel, a discharge-tube in the bottom thereof, a filling-neck opening through the side, a branch tube, through which the neck communicates with the vessel, a valve-seat in the end of said tube, and a ball-valve closing said tube when the vessel is upright and opening the vessel when tilted, substantially as described.

H. H. HULL.
